UNITED STATES PATENT OFFICE.

JAMES HILLS HARTRIDGE, OF LONDON, ENGLAND.

BOX.

SPECIFICATION forming part of Letters Patent No. 460,866, dated October 6, 1891.

Application filed April 9, 1891. Serial No. 388,306. (No model.)

To all whom it may concern:

Be it known that I, JAMES HILLS HARTRIDGE, a subject of the Queen of Great Britain, residing at Ryland Road, London, in the 5 county of Middlesex, England, have invented certain new and useful Improvements in Boxes, of which the following is a specification.

My invention relates to improvements in boxes suitable for holding small articles and 10 for toilet preparations, ointments, powders, medicaments, &c., and for like uses.

To clearly explain the nature of my invention, I will describe it with reference to the accompanying drawing, in which the figure 15 is a central section of the box.

In the form of box shown a rim *a* is employed, having vertical sides, and in this is inserted what may be termed the "body" *b* of the box, consisting of a stamped cup or inverted dome-shaped receptacle having vertical sides. This vertical portion extends above the rim, as shown at *c*, so that a shoulder is provided for the reception of the lid *d*. The lid is preferably stamped up in the form 25 shown, the edges being rounded and the top recessed.

The inverted dome-shaped receptacle or body is of advantage when the box is used for pastes or creams, as it enables the whole 30 of the contents to be readily removed, which

is not the case with ordinary ointment-boxes, in which the contents lodging in the corners is usually wasted, and it is similarly advantageous in the case of small articles.

The material of which the box is made may 35 be metal, card-board, or the like, capable of taking and retaining the shape given it by the stamping-dies.

Having now particularly described and ascertained the nature of my said invention 40 and in what manner the same is to be performed, I declare that what I claim is—

In combination, in a box, the supporting-base formed of a bottomless rim, the inner cup independently formed and having its 45 sides attached to and projecting above the upper portion of the rim, said cup having a rounded bottom, forming a continuation of the sides down to the lower plane of the rim and constituting the box-bottom, said bottom 50 being joined to the sides by a rounded corner, and the cover *d*, substantially as described.

In testimony whereof I have hereunto set my hand in the presence of two subscribing 55 witnesses.

JAMES HILLS HARTRIDGE.

Witnesses:

ALLEN P. JONES,

JAMES BOLES.
